KEYING

George Lindley Usselman, Port Jefferson, N. Y.,
assignor to Radio Corporation of America, a
corporation of Delaware

Application June 10, 1936, Serial No. 84,435

10 Claims. (Cl. 178—66)

This invention involves a novel method of and means for keying oscillatory energy. More in particular this invention involves the method of and means for keying the potential of the suppressor grid of an electron discharge tube of the pentode type the other electrodes of which are connected in alternating current circuits adapted to operate at signalling frequencies. By applying a negative voltage to the suppressor grid of a pentode tube the operativeness of the tube which may be included in a transmitter stage is controlled.

Other methods of and means for keying tube transmitter stages known in the art operate on the control grid or screen grid potential. These methods and means produce considerable reaction on the transmitter driving stage whereas the present method and means of my invention has little or no effect on the transmitter driving stage or preceding stage.

In describing my invention reference will be made to the attached drawings through which like reference characters indicate like parts and in which,

Figures 1 and 2 show for purposes of illustration, circuit arrangements including means for relaying and amplifying waves of carrier frequency and for keying the same. The keying in both modifications is accomplished in a pentode stage and where several of the tubes are operated from a single source of potential, the load on the said source of potential is maintained constant in accordance with my invention by means of an additional tube operated by the keying means which places a load on the potential source when the tube or tubes supplied thereby are keyed off and removes said load when the said tube or tubes are keyed on. This compensation action is accomplished in the keyed stage in Figure 1 and in an additional amplifier stage in Figure 2. The output of the keyed stage in Figure 1 and of the additional amplifying stage of Figure 2 is supplied to a line or aerial directly or after further amplification.

Referring to the drawings both figures show transmitters comprising, a radiating system or transmission line A, a power amplifier or frequency multiplier, or both, B connected at its output to the antenna or transmission line A. The input of B in Figure 1 is coupled as shown to the output of a keyed stage C. In Figure 2 B is coupled at its input to an amplifier stage J which is coupled to the keyed stage C. The amplifier stage J of Figure 2 comprises a pair of electron discharge devices V₃ and V₄, of any type

shown, for illustration as being of the pentode type, having their control grids 1 and 1' and anodes connected in a push pull amplifier circuit. The anodes of the tubes V₃ and V₄ are connected in push pull relation by a tuned circuit 10 and are supplied by potentials from a source 12. The screening electrodes 2 and 2' of the tubes V₃ and V₄ respectively are supplied with direct current potentials from the source 12 by way of similar impedances Z and Z'. The suppressor grid electrodes 3 and 3' of tubes V₃ and V₄ are also supplied by the appropriate operating potentials from the source 12 by way of other impedances Z'' and Z''. The control grid electrodes 1 and 1' of tubes V₃ and V₄ are connected as shown by way of coupling condensers 14 and 16 and radio frequency choking inductances or impedances RFC and RFC' to the tuned output circuit 22 of a stage C. Operating potentials for the control electrodes 1 and 1' of tubes V₃ and V₄ are supplied from a source 20 by way of an additional impedance Z₀ connected as shown. The keyed stage C in both figures comprises a pair of electron discharge devices V₁ and V₂ of the pentode type having their anodes connected in push pull relation by the tuned output circuit 22 which is connected to a point on the source 12 so that both stages derive their anode potential from the same source, although separate source may be provided if it is desirable.

The screening electrodes 2 and 2' of tubes V₁ and V₂ are also supplied with direct current potential from source 12 by way of impedances Z₁ and Z₂ connected as shown. The control electrodes 1 and 1' of tubes V₁ and V₂ are supplied with excitation voltage from a source of wave energy E connected as shown by coupling condensers 26 and 28 and radio frequency choke inductances RFC₁ and RFC₂ to said control electrodes. Operating potentials for the control electrodes 1 and 1' of tubes V₁ and V₂ are supplied from a source 30 connected as shown by way of an additional impedance Z₃ between said control electrodes and cathodes of said tubes. The excitation voltages in E may be of any frequency appropriate for signalling purposes and E may be an oscillator or an oscillation amplifier or multiplier or both. The voltages from E are relayed and keyed in stage C in a manner described more in detail hereinafter, and impressed on B either directly or after being amplified or frequency multiplied or both, in J.

The keying circuit for stage C in both figures comprises a source of keying current KU connected as shown with an impedance R₁ across

which the keying potentials may be set up. The impedance R_1 is connected as shown between the control grid and cathode of an electron discharge device H . The anode of H is connected to the 5 cathode of H by a potentiometer resistance R_3 and an additional resistance R_2 . The potentiometer resistance R_3 may be shunted by any direct current source D such as a battery or a rectifier. A selected point on R_3 is connected by 10 a lead 38 and the resistances or impedances Z_4 and Z_5 to the suppressor grid electrodes 3 and 3' of tubes V_1 and V_2 .

High frequency currents may be shunted around the direct current potential sources connected with the electrodes 1, 2, 3 and 1', 2', and 3' of tubes V_1 , V_2 , V_3 and V_4 by by-passing condensers C connected as shown. High frequency potentials appearing in the anode circuits of stages C and J may be shunted around the direct 15 current sources in a similar manner by by-passing condensers C connected as shown.

The keying circuit operates as follows. It may be seen that the suppressor grids are connected to a suitable point on resistor R_3 near the negative 20 end of rectifier D in Figures 1 and 2. The negative terminal of rectifier D is connected to ground through resistor R_2 . The positive terminal of rectifier D is connected to the anode of tube H . When the keying unit KU impresses a negative 25 potential on the control grid of tube H the anode current of tube H is blocked and the suppressor grids 3 of tubes V_1 and V_2 of the keyed stage C has zero voltage or a few volts positive potential impressed on them through rectifier D and resistor R_2 . In this condition the carrier signal is 30 transmitted. When the output voltage of keying unit KU is zero then resistor R_1 maintains the grid potential of tube H at substantially zero potential and anode current flows in tube H . 35 This in effect, connects the positive terminal of rectifier D to ground through the relatively low impedance of tube H . This then causes the potential of the negative end of rectifier D to be relatively high above ground. Consequently a 40 high negative potential is applied to the suppressor grids of keyed stage C . In this case the anode currents in tubes V_1 and V_2 are cut off and no carrier signal is transmitted. In this way the 45 transmitter is keyed.

Since the anodes and screen grids of tubes V_1 and V_2 of the keyed stage of Figure 1 and the like electrodes of the tubes V_3 and V_4 of the amplifier stage in Figure 2 draw their direct current from the source 12, a variable load is placed 50 on this source during keying operations. In order to regulate the power load I supply an additional compensating or absorbing tube F having its control grid 40 connected as shown to the upper terminal of resistance R_1 , its cathode grounded and its anode 42 connected as shown by way of a resistance R to a positive point on the source 12. As will be explained in detail hereinafter the tube F draws current when the tubes V_1 and V_2 55 are cut off whereas the tube F is cut off when the tubes V_1 and V_2 draw current.

In some cases it may be desirable to key in one stage and compensate in the same stage. In other cases it is desirable to key in one stage and compensate in a later stage. In Figure 1 compensation is accomplished in the keyed stage by connecting the anode of H and resistance R to the supply source for the anodes of V_1 and V_2 . In Figure 2 compensation is accomplished in a later 70 stage, that is, the stage J , by connecting the 75

anode of H and R to the supply lead or source for the anodes and screen grids of V_3 and V_4 .

In describing more in detail the purpose of my novel compensating circuit and the operation thereof it is noted that where the plate rectifier has a large amount of smoothing it is desirable to accomplish the keying of the transmitter without appreciable variations in the rectifier load. This is accomplished by the use of the compensator tube "F" which carries in its anode circuit a 10 part or all of the rectifier load when the anode current of the tubes in the radio frequency stages C or J of the transmitter is cut off or reduced by keying. The grid 40 of compensator F is connected to the keying unit KU , and to resistor R_1 15 as shown in Figures 1 and 2. The anode 42 of compensator tube F is connected to the plate rectifier or anode power source 12 through the power absorbing resistor R . It may be seen that when zero potential is applied to the grids of tube 20 H and tube F by keying unit KU both of these tubes are conductive and signal and anode current is cut off or reduced in the transmitter stages while normal compensating current flows through the compensating circuit comprising the anode 25 to cathode of F and resistance R . The compensating current is substantially equal to the decrease in current in the transmitter stages caused by keying. The tube F absorbs part of the rectifier output voltage of rectifier or source 30 12 and the resistor R absorbs the remainder, which is usually the greater part, if the compensating circuit is adjusted correctly. Naturally the tube F and resistor R in the compensating circuit must be correctly selected for optimum 35 results. When the keying unit output is at a high negative potential, the anode current is cut off in compensating tube F and keying tube H . In this case anode current flows in the radio frequency tubes of stages C in Figure 1 and C and J of Figure 2 and signal is sent out while the current in the compensating circuit has been cut off.

It can be seen that as described the rectifier load current and voltage will remain substantially constant, which was the desired condition. By connecting R to or near the point on 12 at which the tubes V_1 and V_2 draw their anode potential, compensation can be primarily accomplished for stage C . By connecting R to or near the point on 45 12 where the tubes V_3 and V_4 draw their anode potential, compensation can be accomplished primarily for stage J . It is usually most desirable to compensate for the stage which draws the most 50 current or load from the rectifier.

It should be observed that any desirable number of tubes may be operated in parallel at each place where I have shown a single tube in the circuits of Figure 1 and Figure 2. Moreover, any stage in the transmitter may be keyed which 55 seems desirable. The keyed stages utilize tubes of the pentode type. Tubes of any type such as triodes or four-electrode tubes may replace the tubes in the stage J or the tubes H and F as long as such other tubes have the desired operating 60 characteristics.

I claim:

1. In a telegraphy system an electron discharge tube of the pentode type having an input electrode, an output electrode, a cathode and a suppressor grid electrode located between said output electrode and the remaining electrodes, alternating current relaying circuits connected with said input and output electrodes, a source of potential for maintaining said output electrode 70

- positive relative to said cathode, a source of potential for producing operative potentials between said input electrode and cathode, a source of potential and a resistance in parallel connected 5 to said suppressor grid and to said cathode, a keying tube having its output electrodes coupled in circuit with said last named source, the connections between said resistance and suppressor grid being such that said suppressor grid is negative 10 when the impedance of said keying tube is low and means for changing the potential on the input electrodes of said keying tube at signal frequency to vary the impedance between the output electrodes of said keying tube and thereby 15 vary the potential of said suppressor grid and the ability of said first tube to relay alternating current.
2. In a telegraph system an electron discharge tube of the pentode type having an input electrode 20 excited by wave energy to be keyed, an output electrode, a cathode and a suppressor grid electrode located between said output electrode and the remaining electrodes, a source of potential connected to the output electrode for maintaining 25 said output electrode positive relative to said cathode, means for producing operative potentials between said input electrode and cathode, a source of potential and a keying tube impedance connected together and to said suppressor grid 30 and cathode for maintaining said suppressor grid negative relative to said cathode when said keying tube impedance is relatively low, an additional electron discharge tube having its anode and cathode connected to said first named source 35 of potential said additional tube having a control electrode and means connected with said keying tube and with said additional tube for simultaneously increasing the impedance of said keying tube, thereby reducing said negative potential 40 between said suppressor grid and cathode and reducing the impedance of said additional tube to control the operativeness of said first tube and additional tube in an inverse sense.
3. In a telegraphy system an electron discharge tube of the pentode type having an input electrode excited by wave energy to be keyed, an output electrode connected with an output circuit, a screen electrode, a cathode and a suppressor grid electrode located between said output electrode 45 and the remaining electrodes, a source of potential connected to the output electrode for maintaining said output electrode positive relative to said cathode, means for producing operative potentials between said input electrode and cathode, a source of potential shunted by a resistance connected to said suppressor grid and to 50 said cathode, a keying tube having output electrodes coupled in shunt to a portion of said last named source to control the potential developed 55 across said source and supplied to said suppressor grid, said keying tube having input electrodes coupled to a source of signals, an additional electron discharge tube having its anode and cathode connected to said first named source of potential 60 and means connecting the input electrodes of said additional tube to said source of signals whereby the operativeness of said first named tube and the operativeness of said additional tube are controlled in an inverse sense so that the wave energy 65 is keyed at signal frequency and the load placed by said first and additional tubes on said first source of potential is substantially constant.
4. In a signalling system an oscillator circuit, an electron discharge tube including a cathode, a suppressor grid, a control grid, an anode and a 70 shield grid, an input circuit connected between said control grid said cathode and said oscillator circuit, an output circuit connected between said anode and cathode, a source of potential in said output circuit, a second source of potential connected to said cathode, a connection between a point on said second source of potential and said suppressor grid, a keying tube having a cathode coupled to the cathode of said first tube and an output impedance connected to said second source 75 of potential, means for controlling the impedance of said keying tube in accordance with telegraph signals for controlling the potential applied by said second source of potential to said suppressor grid in accordance with said telegraph signals for correspondingly rendering said oscillator circuit effective upon said electron tube system, an additional tube having its output connected to said first named source of potential and means for controlling the operativeness of said additional tube inversely relative to the effectiveness of said first named electron tube system.
5. In a telegraph system, a pair of electron discharge devices each having a cathode, a control grid, an anode, and a suppressor grid electrode, alternating current relay circuits connected between said anodes and cathodes and said control grids and cathodes, a source of direct current potential for maintaining said anodes positive relative to said cathodes, a source of direct current potential for producing an operative potential between said control grids and cathodes, a second source of potential connected by a resistance to said cathodes, a keying tube, a circuit connecting the impedance of said keying tube to 30 said second source of potential and said second source of potential to said suppressor grids for maintaining said suppressor grids negative a substantial amount relative to said cathodes when said keying tube impedance is relatively low, and 35 means for varying the impedance of said keying tube in accordance with telegraph signals to vary the potential of said suppressor grids in accordance with said telegraph signals to control the operativeness of said pair of tubes in accordance 40 with said telegraph signals.
6. In a telegraph system, a pair of electron discharge tubes of the pentode type each having a cathode, a control grid, an anode, and a suppressor grid electrode, alternating current relay 45 circuits connected between said control grids and cathodes and between said anodes and cathodes, a source of direct current potential connected between said anodes and cathodes, a second source of potential and a keying tube impedance in 50 series, a connection between said series circuit and said suppressor grid electrodes and said cathodes, a source of keying potentials, said keying tube having a control grid connected to said source of keying potentials to thereby control the 55 impedance of said keying tube in accordance with said keying potential and consequently control the potential between said suppressor grids and cathodes of said pair of tubes in accordance with said keying potentials.
7. In a telegraph system, a pair of electron discharge tubes of the pentode type each having a cathode, a control grid, an anode, and a suppressor grid electrode, alternating current relay 60 circuits connected between said control grids and cathodes and between said anodes and cathodes, a source of direct current potential connected between said anodes and cathodes, a second source of potential, a keying tube having an anode and a cathode and a control grid, a circuit 65

connecting the anode and cathode of said keying tube and said second source of potential in a series circuit, a connection between said series circuit and said suppressor grid electrodes and 5 said cathodes, a source of keying potentials connected to the control grid and cathode of said keying tube, and an additional electron discharge device having a control grid connected to said source of keying potentials and an anode connected to said first named source of potential.

10. In a telegraph system, an electron discharge device of the pentode type having a control grid, a cathode, an anode, and a suppressor grid electrode, alternating current relaying circuits connected between said control grid and cathode and between said anode and cathode, an electron discharge tube amplifier having a control grid and a cathode coupled to the anode of said first named tube, said amplifier having an anode connected 15 to a source of direct current potential, a second source of direct current potential, a keying tube impedance and a resistance connected in series with said second source of direct current potential, a second resistance connecting said second source of direct current potential to said suppressor grid, a connection between said first resistance and the cathode of said electron discharge device, and means for varying the impedance of 20 said keying tube and simultaneously loading and unloading said first source of direct current potential.

15. In a telegraph system, a pair of electron discharge devices of the pentode type each having a control grid, a cathode, an anode, and a suppressor grid electrode, alternating current circuits connected between said control grids and cathodes and between said anodes and cathodes, an electron discharge tube amplifier having a control grid and a cathode coupled to the anodes 25 of said first named tubes, said amplifier tube having an anode connected to a source of direct current potential, a second source of direct current potential, a resistance in parallel with said second source of direct current potential, connec-

tions between the suppressor grid electrodes and cathodes of said first named pair of tubes and said resistance, a keying tube having its output electrodes connected in series with said second named source of direct current potential and its 5 input electrodes connected with a source of keying potentials and an absorber tube having its output electrodes connected to said first named source of direct current potential and its input electrodes coupled with said source of keying 10 potentials.

10. In a signalling system an electron discharge device of the pentode type having an input electrode, an output electrode, a cathode and a suppressor grid electrode located between said output electrode and the remaining electrodes, an alternating current relay circuit connected between said input electrode and cathode, an alternating current output circuit connected between said output electrode and cathode, means for 15 maintaining said output electrode at a positive direct current potential relative to said cathode, means for producing an operative direct current potential between said input electrode and cathode, a second source of potential and impedance connected together, means connecting said second source of potential and impedance to said suppressor grid and to said cathode, a modulator tube having output electrodes coupled in circuit with said last named source of potential, the connections between said impedance and suppressor grid and cathode being such that said suppressor grid is negative relative to said cathode when the impedance of said modulator tube is low, and means for controlling the potential on the input 20 electrodes of said modulator tube at signal frequency to control the impedance between the output electrodes of said modulator tube and thereby control the potential of said suppressor grid relative to said cathode and consequently the ability 25 of said device to relay alternating current from said input circuit to said output circuit.

GEORGE LINDLEY USSELMAN.
